(57) **CLAIM**

An ornamental design for a control part of an electronic device, as shown and described.

DESCRIPTION

FIG. 1 is a front elevational view of a first embodiment of a control part of an electronic device showing our new design;

FIG. 2 is a bottom view of the control part of FIG. 1.

FIG. 3 is a top plan view of the control part of FIG. 1.

FIG. 4 is a right side elevational view of the control part of FIG. 1.

FIG. 5 is a left side elevational view of the control part of FIG. 1.

FIG. 6 is a perspective view of the front, right and top sides of the control part of FIG. 1.

FIG. 7 is a front elevational view of a second embodiment of a control part of an electronic device showing our new design;

FIG. 8 is a bottom view of the control part of FIG. 7.

FIG. 9 is a top plan view of the control part of FIG. 7.

FIG. 10 is a right side elevational view of the control part of FIG. 7.

FIG. 11 is a left side elevational view of the control part of FIG. 7; and,

FIG. 12 is a perspective view of the front, right and top sides of the control part of FIG. 7.

In FIGS. 1–12, the rear surface of the control part, which does not constitute an integral part of the claimed design, is not illustrated.
